UNITED STATES PATENT OFFICE.

GEORGE H. NURNBERGER, OF WELGA, ILLINOIS.

RAIL-SPIKE.

1,042,955.

Specification of Letters Patent. Patented Oct. 29, 1912.

Application filed March 19, 1912. Serial No. 684,919.

To all whom it may concern:

Be it known that I, GEORGE H. NURNBERGER, a citizen of the United States, residing at Welga, in the county of Randolph 5 and State of Illinois, have invented new and useful Improvements in Rail-Spikes, of which the following is a specification.

This invention relates to rail spikes and has for an object to provide a device of this 10 character which may be securely braced against the rail tie so as to prevent the spike from bending back under the lateral expansion or movements of the rail with which the spike is associated.

15 In the drawing forming a portion of this application and in which like letters of reference indicate similar parts in the several views:—Figure 1 is a side view of the spike. Fig. 2 is a rear view thereof. Fig. 3 is a 20 view similar to Fig. 1 showing the spike associated with a rail tie and rail.

The spike comprises a shank or stock 1 which is pointed at its lower end as at 2. The shank 1, while shown as of rectangular 25 configuration may be of any suitable obvious shape which may be found most desirable for the purpose. At the upper end the shank is provided with a head 3 having parallel sides 4 which extends laterally beyond 30 the shank 1. These sides merge into the forwardly extending lip 5 of the spike as shown.

Beneath the head, the spike is provided 35 with an integral brace 6 having a relatively broad horizontal surface 7 which extends beyond the opposite sides of the shank. The sides of the brace 6 are curved upward as at 40 8 into the lower surface of the head 3, being spaced from the under surfaces of the head so as to present relatively long intervening 45 grooves therebetween for the reception of a crowbar, like implement or extracting tool, not shown. The forward surfaces 9 of the brace 6 are beveled upwardly and outwardly 50 in the direction of the underside of the lip

5 of the spike. These surfaces 9 conform with the angle of a fish plate as shown in Fig. 3 and are adapted to contact therewith. In this manner the spike is provided with a plurality of contacting surfaces to engage 50 the object to be anchored. That is to say that while the surfaces 9 engage against the fish plate the lip 5 engages against the rail, as shown.

From the construction described it is evident that the surface 7 securely braces the shank of the spike so as to prevent the bending of the latter on lateral movement of the rail.

I claim:—

A spike comprising a shank having a head at one end, the said head being extended forwardly from the side of the shank so as to present a relatively broad lip, the sides of the head being extended laterally from the 60 opposite sides of the shank, and an integral anchoring member formed upon the shank and disposed below the plane of the head and having a horizontally disposed contacting surface having a length transverse the 65 spike greater than the similar dimension of the head and provided with sides which are curved upward in the direction of the lateral sides of the head, the anchoring member at the juncture of the horizontally disposed contacting surface and the curved sides presenting vertical edges of material 70 thickness whereby to provide an anchoring member in rear of the spike having a dimension transverse the spike exceeding the similar dimension of the head, and a material thickness to provide an effective resisting element.

In testimony whereof I affix my signature in presence of two witnesses.

GEORGE H. NURNBERGER.
